US0D1026140S

(12) **United States Design Patent** (10) Patent No.: **US D1,026,140 S**
(45) Date of Patent: ** May 7, 2024

(54) **ROPE GRIP EXERCISE DEVICE WITH LOOPED STRAP**

(71) Applicant: **Derek Mitchell**, Huntingdon Valley, PA (US)

(72) Inventor: **Derek Mitchell**, Huntingdon Valley, PA (US)

(**) Term: **15 Years**

(21) Appl. No.: **29/768,323**

(22) Filed: **Jan. 28, 2021**

(51) LOC (14) Cl. **21-02**

(52) U.S. Cl.

USPC **D21/729**

(58) **Field of Classification Search**

(57) **CLAIM**

The ornamental design for a rope grip exercise device with looped strap, as shown and described.

DESCRIPTION

FIG. 1 is a front view of a rope grip exercise device with looped strap;

FIG. 2 is a rear view thereof;

FIG. 3 is a right-side view thereof;

FIG. 4 is a left-side view thereof;

FIG. 5 is a top view thereof;

FIG. 6 is a bottom view thereof; and,

FIG. 7 is a perspective view thereof.
